UNITED STATES PATENT OFFICE.

WILLIAM QUEENAN AND CHARLES FARWELL, OF AURORA, ILLINOIS.

DOOR FOR FREIGHT-CARS.

1,244,078.

Specification of Letters Patent. Patented Oct. 23, 1917.

Original application filed March 6, 1916, Serial No. 82,420. Divided and this application filed October 9, 1916. Serial No. 124,513.

To all whom it may concern:

Be it known that we, WILLIAM QUEENAN and CHARLES FARWELL, citizens of the United States, and residents of Aurora, in the 5 county of Kane and State of Illinois, have invented certain new and useful Improvements in Doors for Freight-Cars, of which the following is a description, reference being had to the accompanying drawings, 10 which form a part of our specification.

Our invention relates more particularly to grain doors for railway cars; having for its object the provision of a moisture or storm-proof, as well as a grain-tight construction.

15 A further object of our invention is to provide a releasing or unloading door-section, operable independently of the main door and so arranged as not to interfere with the main door, nor with the use of the 20 car for shipment of other commodities when desired.

The invention contemplates a construction which may be used in connection with the present type of freight car, whether of 25 wood or steel construction; permitting the main door to be mounted and operated in the usual sliding manner; the purposes and advantages of the invention being more readily apparent from the following detailed description of the drawings, wherein:-

Figure 1 is a side elevation of the lower part of the main car-door with our improved grain-releasing door-section shown in closed 35 position.

Fig. 2 is a sectional view, shown in perspective, and taken on the line 2—2 of Fig. 1, looking in the direction of the arrows.

Fig. 3 is a detail sectional view, taken 40 on line 3—3 of Fig. 1, looking in the direction of the arrows.

Fig. 4 is a perspective view, taken on the line 4—4 of Fig. 1, looking in the direction of the arrows.

45 Fig. 5 is a sectional view, taken on the line 5—5 of Fig. 1, looking in the direction of the arrows.

Fig. 6 is a sectional view similar to Fig. 5, with the grain or releasing door-section 50 shown in open position.

In the exemplification of the invention, as illustrated in the drawings, our improved grain-door is shown applied to a freight car

of wood construction, wherein the main door 10 may be supported by suitable hangers 55 adapting the door to be slid along the car-side on a suitable overhanging track or bar.

The lower part of the door 10 is shown provided with a steel or metallic plate 11, extending full width of the door and bent 60 inwardly beneath the door, with the lower edge of the plate disposed in the vertical direction, as shown at 12 in Fig. 4.

Secured to the side sill 13 of the car underframe, by means of suitable bolts and 65 in spaced relation with the side sill, is an angle iron or beam 14 having one leg or portion presented upwardly and into close relation with the depending edge 12 of the door-plate 11; while the other leg or portion of the beam 14 is presented outwardly 70 away from the car side. The beam or angle iron 14 is secured to the side sill of the car underframe and maintained in its spaced relation thereto by means of suitable blocks, as 75 at 15 in Fig. 2, through which the sustaining bolts 16 pass. The rear end or side of the door 10 is shown provided with a metallic plate 17, more clearly shown in Fig. 4, of special construction and extending preferably the full height of the door. The plate 80 17 is somewhat in the nature of a channel in cross section, as shown in Figs. 5 and 6; the lower end of the plate 17 being bent so as to overlap the main portion of plate 11 85 and arranged to depend somewhat beneath the lower end of the door 10, thereby overlapping the end of the angle-iron or beam 14.

The inner face of the channel member or plate 17, at the lower end thereof, is 90 shown provided with the zig-zag or stepped rib 18 adapted to fit into a notch or slot formed in the end of the beam 14, as shown in dotted lines in Figs. 5 and 6. The rib 18 is preferably of the formation shown, although any suitable formation of rib or ridge 95 may be provided which will fit into a suitable slot or notch in the end of the beam 14 and thus provide a grain-tight relation at the lower rear corner of the door between 100 the member or plate 17 and the beam 14.

The side sill 13 is shown provided with a stop-bar or strip 19 extending the full length of the door-opening at a point just beneath the threshold; the upper edge of 105 the strip being shown beveled, see Fig. 4, in

order to properly shed the grain and at the same time provide greater space for the passage of the grain. The strip 19 is provided with suitable apertures to receive the 5 pins or lugs with which the blocks 15 are provided adjacent their lower sides and as indicated in dotted lines at 20 in Fig. 2; the purpose of the pins or lugs 20 being to prevent the blocks 15 turning on the securing 10 bolts 16.

The grain-releasing door-section, as illustrated in the drawings, comprises a plate or member 21 which extends substantially the full length of the main door opening and is 15 of a width somewhat greater than the distance between the bar or strip 19 and the beam 14, so that when the plate or member 21 is in the horizontally disposed position, which is the closed position, it will overlap 20 or rather extend beneath the beam 14 and the bar or strip 19, as very clearly shown in Fig. 4.

The plate or member 21 is preferably in the nature of a metal sheet provided with a 25 reinforcing member or angle-iron 22 riveted or otherwise secured thereto and extending lengthwise thereof.

The ends of the member or plate 21 are provided with hinge members 23 secured 30 adjacent the outer longitudinal edge so as to bring the pivoted point slightly beyond and beneath the outer edge of plate 21, as shown in Figs. 4, 5 and 6. The hinge-members 23 (one at each end of plate 21, see 35 Fig. 1) are adapted to coöperate with hinge-members 24, shown and secured to the ends and lower surface of the beam 14; the hinge-member 24 being shown adapted to receive the pintles or trunnions of the members 23. 40 With the hinge-members 23 secured adjacent the outer longitudinal edge of member 21, the latter is allowed to swing downwardly into the position shown in Fig. 6, substantially in the same vertical plane as 45 the beam 14, and thereby provide a clear opening or passage for the outward flow of grain lying adjacent the main door.

The inner longitudinal edge of member 21 is supported in closed or horizontal position 50 by the supporting member or bar 25, shown in the nature of an angle iron and disposed lengthwise of member 21 so as to provide proper support therefor and maintain the member 21 in close contact with the under 55 side of the strip or bar 19.

The supporting member or bar 25 is pivotally supported by means of links 26 which are pivotally mounted on suitable bolts 27 secured to the side sill or to the side of the 60 underframe of the car; the bolts 27 being of such construction as to permit free swinging movement of links 26.

In the illustration of our invention, it is shown applied to a car of wood construction, 65 and for that reason the side sill 13 is prefer-

ably provided with a metallic plate 28 extending the full length of the door-opening and insuring a smooth working surface for the oscillatingly mounted supporting bar 25 and the links 26. It will be understood, of course, that where the car and underframe are of metallic construction, the additional plate 28 may be eliminated. 70

At a point preferably intermediate of the links 26, the supporting bar 25 is provided with an operating lever 29, more clearly shown in Fig. 4. The operating lever 29 is pivotally secured at its upper end to the supporting bar 25 and at an intermediate point on the bolt 30 secured to the car underframe or side sill. 75

The upper ends of the links 26 and operating lever 29 may have any suitable pivotal connection with the supporting bar 25 as, for example, by means of pins 31, so as to permit of proper movement of the supporting bar 25 relative to the links and operating lever. 80

The operating lever 29 is shown as preferably extending a sufficient distance beneath the side sill or car underframe so as to enable easy operation thereof; and the lever is shown provided with a bracket or lug 32 formed so as to extend slightly to one side of the lever, in order that the bracket or lug 32 may be brought into alinement with the keeper 33 secured to the side sill in any suitable manner. The keeper 33 and bracket 32 are provided with correlated openings adapted to receive the seal-pin 34 attached to the car underframe by means of a suitable chain 35; the lower end of the seal-pin 34 being provided with a suitable opening to receive the usual sealing wire or means employed in railroad practice. 90 95

As is evident from the construction shown and described, the supporting bar or member 25 may be made to drop or swing downwardly until it comes into contact with the pivotal points or bolts 27 and 30 of the links 100 and operating lever, respectively, as the length of the operating lever 29, intermediate of its pivotal point 30 and its pivotal point on supporting bar 25, is preferably equal to the length of the links 26. When 110 the supporting bar 25 has been swung downwardly as described, the inner longitudinal edge of plate or member 21 will be unsupported and therefore caused to swing on its hinges or pivotal points 23, 24, which will 115 release the grain supported thereby and located adjacent the main door opening. 120

Intermediate of the beam 14 and the side sill, towit at a point beneath the door opening and at the side thereof, we prefer to 125 provide filler blocks, as shown at 36, see Fig. 2, having upper beveled ends so as to properly shed the grain while it is being discharged.

The ends of the door-section or member 130

21 and its hinges are preferably made to extend slightly beneath the filler blocks 36 in order that grain-tight points may be provided.

5 With our improved construction, the releasing door or member 21 will permit the grain to be discharged from the car until a sufficient quantity has been released to relieve the pressure against the main door 10 and permit opening thereof.

10 The releasing door or element, as shown in the drawings, is so located with reference to the main door opening as to in no way interfere with the use of the car for 15 shipment of other commodities, during which time the releasing door or element may be left in raised or closed position where it will be out of the way and protected against injury. As is evident from 20 the construction shown and described, a grain-tight relation between the releasing door-section and the main door is provided and also a weather or moisture-proof construction obtained, because the outwardly 25 presented leg of the beam 14 will shed rain and the like and prevent it entering the joint or connection between the releasing door and the lower face of the beam. In order that the section 21 may be readily 30 returned to closed position, we show it, or rather the reinforcing member 22, secured thereto, provided with a handle as at 37 in Fig. 1.

35 We have shown and described what we believe to be the simplest and best form of the invention, but it will be understood that the same may be varied in certain details of construction without, however, departing from the spirit of our invention.

40 What we claim is:—

1. In combination with a freight-car door slidably mounted on the car side with the lower part of the door in spaced relation with the threshold of the door-opening, 45 means mounted beneath the door-opening on the car side in spaced relation therewith and having lapping engagement with the bottom of the door, and movable means for closing the space between said first mentioned means and the car side.

50 2. In combination with a freight-car door arranged to provide space intermediate of the threshold of the door-opening and the door when the latter is in closed position, means mounted beneath the door-opening in spaced relation with the car side and having lapping engagement with the lower end of the door, and movable means adapted to provide a closure for the space 55 between the first mentioned means and the car side whereby grain and the like may be discharged while the door is in closed position.

60 3. In combination with a main car door arranged to provide space intermediate of

the threshold of the door-opening and the door when the latter is in closed position, the lower end of the door being provided with a depending flange coextensive with the door, a fixed member, with which said 70 flange has lapping engagement, arranged in spaced relation with the car side beneath the door-opening, and a releasing member pivotally mounted beneath said fixed member so as to swing into a horizontal position 75 intermediate of the fixed member and the car-side.

4. A freight-car door, the lower end whereof is spaced from the threshold of the door-opening, and means secured in spaced 80 relation with the car side and in lapping relation with the bottom of said door so as to close the space between the door and the threshold, a portion of said means being arranged to swing downwardly and to permit 85 the discharge of grain through said space while the car door is in closed position.

5. A door of the class described mounted so as to provide space intermediate of the threshold of the door-opening and the door, 90 and a section provided with horizontally disposed pivots so as to swing vertically into substantially horizontal position and provide a closure for the space intermediate of the door and the car whereby grain and the 95 like may be discharged while the door is in closed position.

6. In combination with a freight-car door slidably mounted on the car side so as to provide spaced relation between the door 100 and the threshold of the door-opening, means fixedly mounted beneath the door and in spaced relation with the car side, said means having lapping relation with the lower end of the door and provided with a 105 moisture-shedding surface, and closure means movably mounted beneath said first mentioned means for closing the space between the first mentioned means and the car side or to permit discharge of grain while 110 the door is in closed position.

7. In combination with a freight-car door mounted on the car side so as to provide spaced relation between the door and the threshold of the door-opening, means 115 mounted beneath the door-opening and in spaced relation with the car side and having lapping engagement with the bottom of the door so as to provide a moisture-proof connection, means pivotally mounted beneath the first mentioned means and adapted to provide a closure for the space intermediate of the first mentioned means and the car side whereby discharge from the car may be effected with the door in closed position, 120 and means for supporting the moving portion of said closure means in closed position.

8. In combination with a freight-car door mounted so as to provide space between the door and the threshold of the door-opening, 125

a member secured in spaced relation with the car-side and beneath the door, a releasing member pivotally secured to said first member so as to swing vertically beneath the latter when in open position, said releasing member being adapted to swing into horizontal position and thereby close the space between the door and threshold, and means pivotally secured to the car for 10 maintaining said section in horizontal closed position.

9. In combination with a freight-car door slidably mounted on the car side so as to provide a space intermediate of the lower 15 end of the door and the threshold of the door-opening, a member fixedly mounted on the car side in spaced relation therewith and in lapping engagement with the lower end of the door, said member being provided 20 with an outwardly presented weather-shedding surface, a releasing door-section pivotally mounted on the under side of said member so as to swing into vertical alinement therewith when in open position, and 25 means for maintaining said releasing door-section in closed position.

10. In combination with a door slidably mounted on the car-side so as to provide space between the lower end of the door and 30 the threshold of the door-opening, a member mounted in spaced relation with the car-side beneath the door-opening and in

lapping engagement with the door, a second member pivotally mounted beneath said first member so as to swing into horizontal position to close the space intermediate of the first member and the car-side and operable independently of the main door, an element 35 oscillatingly mounted on the car-side and adapted to support the free side of said second member in horizontal closed position, and means whereby said element may be locked in place and movement of the second member prevented.

11. In combination with a freight-car door 45 slidably mounted on the car side so as to provide space intermediate of the door and the threshold of the door-opening, a member fixedly secured beneath the door and in spaced relation with the car side so 50 as to provide an intervening passage, means secured to the door and arranged to have lapping engagement with said member so as to provide moisture-proof and grain-tight connections, a releasing door-section 55 pivotally secured to said member so as to swing vertically, and means secured to the car side and adapted to maintain said door-section in closed position.

WILLIAM QUEENAN.
CHARLES FARWELL.
